UNITED STATES PATENT OFFICE.

FRANK C. DELI, OF CHICAGO, ILLINOIS, ASSIGNOR, BY MESNE ASSIGNMENTS, TO
AUTOPPOINT COMPANY, OF CHICAGO, ILLINOIS, A CORPORATION OF ILLINOIS.

MECHANICAL PENCIL.

Application filed August 30, 1920. Serial No. 406,980.

This invention relates to certain new and useful improvements in lead pencils of the magazine or mechanical type, commonly called "ever-sharp" pencils, and it consists in certain peculiarities of the construction, novel arrangement, combination and operation of the various parts thereof, as will be hereinafter more fully set forth and specifically claimed.

- 10 The principal object of the invention is to provide a pencil of the above mentioned general character, which shall be simple and inexpensive in construction, strong, durable and highly efficient in operation, with its 15 parts so made, arranged, and operating that a plurality of leads may be carried thereby, with one lead in operative position to be advanced through one end of the body of the pencil for use, or retracted, when not for use, 20 to prevent the point thereof being broken or impaired. A further object is to provide means for actuating a plunger for the operative lead of the pencil by the rotation of a shell or member to cause said lead to be 25 advanced or fed forwardly. Still another object is to utilize a part of the plunger operating mechanism as a guide or holder for the operative lead.

A still further object is to so construct the 30 various parts of the device that they may be easily, economically assembled. Various other objects and advantages of the invention will be obvious from the following description and explanation.

- 35 In the accompanying drawing which serves to illustrate an embodiment of the invention—

Fig. 1 is a central longitudinal sectional view of a pencil embodying the invention, 40 showing by continuous lines one end thereof closed by a cap or plug carrying eraser, and by dotted lines about the position the said cap and eraser will occupy when ready for use.

- 45 Figs. 2 to 5 inclusive are cross-sectional views taken on lines 2—2, 3—3, 4—4, 5—5, respectively, looking in the direction indicated by the arrows, and

Fig. 6 is a greatly enlarged longitudinal 50 sectional view of the front end of the pencil.

Like numerals of reference refer to corresponding parts throughout the different views of the drawings.

The reference numeral 10 designates the barrel or body of the pencil, which barrel 55 or body is by preference cylindrical in form and may be made of any suitable dimensions and material, but preferably of metal. This barrel is provided near its front or lower end with an outwardly extended annular 60 bead 11, and near its upper or other end with a similar bead 12 which latter bead is employed for ornamentation only.

Closely fitted to the lower or front portion of the barrel 10, and by preference within the same is a tube 13 which is provided near its upper end or that end thereof located within the barrel 10 with an outwardly extended annular bead 14 which coincides or engages with the bead 11 for the purpose of preventing longitudinal movement of the barrel 10 and the tube 13 with respect to each other.

As is clearly shown in Fig. 1 of the drawing, the tube 13 extends downwardly some 75 distance below the lower or front end of the barrel 10 and has closely fitted thereon the upper portion of a downwardly or forwardly shaped tubular tip in the form of a shell 16 which is provided with a filler 17 80 of any suitable material, such as metal, which filler is fixed to the shell 16 within the same and extends from a point near the lower or front end of said shell upwardly therein to any suitable distance. The filler 85 17 is provided longitudinally and centrally with an opening 18 which terminates at its upper end in an enlargement or socket 19 for the purpose to be presently explained. The front or lower end of the shell 16 is 90 provided with longitudinally and transversely extended incisions or slits 20 which will afford some resiliency to the retracted end of the shell 16 for the purpose of gripping the operative lead 21 of the pencil just 95 above its point.

Located within the barrel 10 at a suitable distance above the bead 11 thereof and by preference on the upper end of the tube 13 is a disk 22 which is provided with a substantially key-hole shaped opening 23 for the reception of a guide member 24 which is by preference made of a single piece of sheet metal bent approximately back upon itself to form a longitudinal channel open 105 at its lower end, as will be readily under-

stood by reference to Figs. 2 to 5 inclusive of the drawings.

The inner portion of the member 24 is by preference circular in cross-section and has 5 extended laterally therefrom a pair of spaced parallel flanges 25 which when the guide member 24 is located in the opening 23 of the disk 22 will by preference extend near the periphery of said disk at their outer or free edges. The upper end of the guide member 24 is supported within the barrel 10 at a suitable distance below the bead 12 thereof by means of a disk 26 which is closely fitted in the barrel and has 10 an opening 23 similar to the opening 23 in the disk 22 and for a like purpose.

In addition to the opening 23 the disk 26 is provided in its periphery with a cut-away portion 27 which is employed for the purpose of permitting leads to be placed in the magazine or space 28 provided by the disks 22 and 26 and the main body portion of the barrel. Located within the inner or tubular portion of the guide member 24 and extended from near the upper end and through the lower or front end of said guide piece is a spiral or coil member 29 which extends at its lower end into the socket 19 of the 20 filler 17 and by preference is secured to said filler by means of solder. Located in the upper portion of the spiral member 29 is a plunger 30 which is provided, preferably, midway between its ends with a laterally extended arm 31 which extends laterally between the flanges 25 of the guide member 24 as will be readily understood by reference to Fig. 3 of the drawing. By this arrangement it is evident that the inner or tubular portion of the guide member 24 will be so held by disks 22 and 26 that it will align with the opening 18 extended longitudinally through the filler 17 of the rotary shell, and it is further obvious that as the spiral member 29 is located within the tubular or inner portion of the guide member 24 the circular opening provided by the coils of the spiral member 29 will align with the opening 18 so that a lead 21 may be inserted at the rear end of the pencil through the spiral 29 to a suitable distance, for instance, until its lower end reaches the lower portion of the opening 18 in the filler of the shell.

The upper end of the tip makes a close fit with the tube 13 for the purpose of appearance and for holding the tip to the pencil. It is obvious, however, that since the arm 31 is at all times retained within the channel provided between the parallel flanges 25, a pull upon the tip will cause the arm to slide downwardly within the channel and through the open lower end thereof, permitting the arm and the spiral to be entirely withdrawn from the pencil. In these circumstances it is manifest also that the plunger may be manipulated

through the medium of the projecting arm 31 to effect a change of the longitudinal position of the plunger within the spiral, thereby facilitating the insertion of a new lead in the latter from either end thereof. 70

When the operative lead is thus positioned, assuming that the plunger 30 and its arm 31 are subsequently located in about the positions shown in Fig. 1 of the drawing, that is, so that the lower end of the plunger will contact with the upper end of the operative lead 21, it is manifest that by turning the shell 16 in the proper direction, which operation will cause the spiral member 29 to turn therewith, the plunger 30 will be caused to move forwardly by reason of the engagement of its arm 31 with the coils of the spiral 29 and thus feed the operative lead 21 forwardly. It is obvious that the reverse movement of the shell 16 85 will cause the plunger 30 to be retracted so that the lead 21 may be pushed inwardly of the pencil so that its point will be protected.

The upper or rear end of the barrel 10 is 90 open and adapted above the bead 12 thereof to receive a cylindrical portion 32 of a milled cap 33, which cylindrical portion may have fitted in its free end an eraser 34 of rubber or like material which may be used 95 by simply removing the cylindrical portion 32 of the cap 33 from the upper end of the barrel 10 and reversing said cap and inserting the cylindrical portion 35 thereof in the open end of the barrel. By my improved 100 construction, it is manifest that by removing the milled cap 33 from the barrel, and by turning the shell 16 in the proper direction, the plunger can be ejected through the upper or rear end of the guide member and 105 barrel, from which parts it can be removed to permit a pencil lead to be inserted in the upper or rear end of the guide member, after which the plunger can be reinserted into the guide member and by turning the shell 110 16 in the proper direction will be caused to eject the operative pencil lead a proper or desired distance through the tapered or front end of the shell. As the arm 31 of the plunger is located between the ends thereof, and by preference midway between its ends, 115 it is obvious that the plunger can be turned end for end when inserting it in the guide member. By this construction no great amount of time or care is necessary in thus 120 assembling the parts.

As shown in the different views of the drawings, the flanges 25 of the guide member are extended laterally therefrom and approach at their free edges the inner surface of the barrel. These flanges not only serve to guide the arm 31 of the plunger in such a way as to prevent wobbling or deflection operation thereof, but also serve to stiffen the guide member as well as to pro-

vide a longitudinally extended partition within the barrel to prevent the pencil leads located within the magazine 28 obstructing the feeding operation of the operative pencil lead by the plunger, which might occur if the flanges 25 were not employed to protect or to prevent the leads in the magazine getting under the arm 31 of the plunger.

Having thus fully described my invention, 10 what I claim as new and desire to secure by Letters Patent is—

1. A pencil, comprising in combination, a body, means therein providing a non-circular axial opening, a tip having a cylindrical portion adapted to telescope over the lower end of said body, a spiral secured to said tip, said spiral being open at both ends, a plunger within said spiral, said plunger having a laterally projecting portion cooperating with the non-circular portion of said axial opening, said tip, spiral and plunger being removable from said body by an end-wise pull in any position of adjustment of the parts, the plunger being thereafter removed from the open upper end of the
2. In a pencil, the combination of a body having an axial opening that is non-circular in cross section, a tip having a cylindrical extension adapted to telescope over the lower end of said body, a tubular member providing a spiral track, said member being open at both ends and being permanently secured to the tip near its lower extremity, 35 a lead advancing plunger in said tubular member, said plunger having a portion adapted to cooperate with said spiral track, said plunger being prevented from rotation by cooperation with the non-circular portion of said axial opening, said tip, tubular member and plunger being removable from the body in any position of adjustment of the parts, whereby upon separation from the body the plunger may be dropped out of the 40 open upper end of said tubular member and a replacement lead placed in the open upper end of the tubular member and the plunger replaced.

FRANK C. DELI.
